UNITED STATES PATENT OFFICE.

MARK ANTHONY, OF SAN FRANCISCO, CALIFORNIA.

STREET OR STATION INDICATOR.

SPECIFICATION forming part of Letters Patent No. 385,985, dated July 10, 1888.

Application filed July 16, 1887. Serial No. 244,541. (No model.)

To all whom it may concern:

Be it known that I, MARK ANTHONY, a citizen of the United States, residing at San Francisco, in the county of San Francisco and State of California, have invented certain new and useful Improvements in Advertising Street or Station Indicators; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a front elevation of my improved automatic station-indicator. Fig. 2 is a vertical longitudinal section of gear-barrel G and spring H. Fig. 3 is a detail top view of barrel G and bar P. Fig. 4 is a top view of barrel G broken away, showing spring H and gear g. Fig. 5 is a front elevation of my indicator with casing J broken away, showing thrust T. Figs. 6, 7, 8, 9, and 10 are detail parts. Fig. 11 is a broken end view of a car with my improved indicator attached. Fig. 12 is a side view. Fig. 13 is a detail front view of the reversing-lever and thrust. Fig. 14 is a detail top view of incline m'. Fig. 15 is a detail view of automatic attachment for steam-cars. Figs. 16, 17, and 18 are modified views.

This invention has relation to automatic station-indicators for railway-cars; and it consists in the construction and novel combinations of parts, as hereinafter set forth.

35 In the accompanying drawings, the letter A designates a box or case, in which the horizontal rolls or drums and the indicating-ribbon carrying the names of the streets or stations are located, this box being preferably provided with a glazed front, A', to protect the ribbon and mechanism.

B designates the trip-drum, and C the free drum, which is connected to its shaft B' by a spring, D, whereby any slack of the ribbon is taken up. A bearing-frame, E, of metal, is secured in the end of the box.

45 F is a vertical-rod connection carrying at its end double pinions a' a' and b' b' and at its middle portion a pinion, c. This rod is pivoted in a collar connected to a shifting-lever,

d, whose stud c' projects through a slot, d', in the case-wall. A shifting-lever is moved to raise or lower the rod F to bring its lower pinions, a' b', or its upper pinions, a b, in engagement with the journal-pinions e e' of the drum shafts or journals. This shifting mechanism is designed to facilitate the reversal of the movement of the drums, so that the indicator-ribbon may be carried in either direction according to requirement.

55 G is a barrel-gear carrying an inside coiled spring, H, one end of which is connected thereto. The inner end of said spring is attached to the winding-stem K, which carries the large lower gear-wheel, g, and the upper ratchet, h, which are rigidly secured to said stem. The barrel-gear engages the middle pinion, e, of the shifting-rod F. The lower gear-wheel, g, engages an intermediate pinion, 60 g', which is engaged by the pinion h' of the winding-rod L, which extends through a bearing in the case-wall and is provided with a handle, l.

65 The upper ratchet, h, of the stem K engages spring-pawl m m of the gear M, which is loose on the stem under the pinion h, so that when the gear M is turned in one direction it will carry the pinion h and stem K, but when turned in the opposite direction it will rotate 70 freely on said stem. The gear M is located above the bearing or frame plate N, as shown, and is in engagement with a toothed bar, P, which is designed to move back and forth in horizontal position when actuated by the devices hereinafter referred to. When moved 75 in one direction, the slide or bar P will turn the gear M to rotate the stem K and wind the spring H in the barrel-gear; but when said slide or bar is moved in the opposite direction, 80 although the gear M is turned, no effect will be produced on the winding-stem. In this manner it is designed to provide means for automatically winding the mainspring H.

85 On the upper surface of the spring-barrel G, 95 at its marginal portion, are provided the stop-lugs n, which are designed to successively engage the angular stop-pawl p, which is pivoted to the frame-plate N. This stop-pawl is provided with a beveled end, r, having 90 a catch shoulder or projection, k, and the toothed slide or bar P is provided with a lat-

erally-projecting pivoted arm t , having a re-
tracting - spring, s , and held by said spring
against a shoulder or bearing of the bar P .
This arm t projects sufficiently to engage the
5 beveled end of the pawl p when the latter is
held in normal position by its spring p' . The
other end of the pawl p is provided with a
downwardly-extending lug or projection, v , which is adapted, when the pawl is in nor-
10 mal position, to engage a stop-lug, n , of the
spring-barrel G . When the slide-bar is moved
in one direction, its lateral arm t engages the
end pawl, p , and turns the latter sufficiently
15 to move its lug v out of engagement with the
stop-lug of the spring-barrel G , allowing said
spring-barrel to rotate under the action of the
mainspring and turn the vertical rod F , which
turns the drums and shifts the indicator-ribbon
20 to show the name of the next station. After
the arm has passed the catch k of the pawl the
latter returns to its normal position, and its
stop-lug is replaced in the path of the stop-
lugs of the spring-barrel, so that the move-
25 ment of said spring-barrel, and consequently
the drums and the indicator-ribbon, is stopped
when the next stop-lug comes into engage-
ment with the pawl p .

If the car to which this attachment is applied
has a perfectly steady motion, it would be suffi-
30 cient to operate the toothed slide by means of
an incline at the side of the track to move the
slide in one direction and a spring in connec-
tion with said slide to retract it; but in prac-
35 tice cars are found to sway when in motion,
and as this irregular or unsteady movement is
less marked near the track, it is designed to
provide the attachment with a vertically-mov-
ing reciprocating slide or thrust bar, T , which
40 is located in the casing or way J . This thrust-
bar is formed with a long bevel or inclined
slot, I , which is curved so that its inclination
becomes more and more parallel with the edge
45 of the bar at its end, so that when its move-
ment commences its action will generally over-
come the inertia of the mechanism and injury
thereto will be avoided. When the thrust-bar is
moved upward by the track device or trip, it
50 actuates the toothed rack-bar to force it in the
operative direction, and when the trip ceases
55 to act the thrust-bar descends under the action
of gravity and reverses the movement of the
toothed bar P . A spring may be employed
in connection with the thrust-bar to hasten its
descent; but this is rarely necessary.

55 To operate the vertical thrust-bar, I pro-
vide a pendent arm, V , extending downward
through a bearing, v' , attached at any conven-
ient part beneath the car, but preferably to a
60 loose collar-connection, Z , on the axle, said
collar-connection being free to allow the axle
to turn therein, but provided with guards to
prevent endwise movement. The arm V is
provided with a roller, z , preferably toothed
65 at its lower end to engage an incline or rack,
 r' , which is connected to the trackway, or in
the cable-way when the attachment is applied

to a cableroad. The arm V is also provided
with a jointed-link connection, t' , which is piv-
oted at its lower end to a crank, w , on the jour-
nal of the roller, and at its upper end to a 70
crank-arm, z' , of a rock-shaft, v'' , which is
seated in a bearing, s' , fastened to the bot-
tom of the car. This rock-shaft also car-
ries a crank-arm, n' , which is set at an angle
75 with the crank-arm z' , and when the roller
is turned the crank-arms are moved to op-
erate the rod-connection w' , which extends
along the bottom of the car to connect with
the horizontal thrust J' , which is seated in
80 the bearing Q , and is formed with a beveled
end or guide portion, I' , which, when said
thrust is moved forward, engages an arm, d' ,
of a rock-shaft, e' , which also carries an arm,
85 g' , to which is connected the lower end of the
rod extension h' of the vertically-reciprocat-
ing thrust-bar T . It will be observed that the
thrust-bars T and J' may be so made that if
90 their movements are extended beyond a point
sufficient to exactly operate the mechanism
connected it will not affect the proper oper-
ation of said mechanism. This is effected by
extending the thrust to provide a straight
bearing, k' , at the end of the bevel in the di-
95 rection of motion. In this manner perfect ac-
tion of the thrust-bar is secured, notwithstanding
any irregular movements below.

When the devices are to be used in connec-
tion with steam railway-cars, it will often suf-
fice to extend the thrust-connection w' beyond
the side of the car, as indicated in Fig. 15 of 100
the drawings, this thrust-connection being
provided with an end roller to engage a rack
or incline at the side of the trackway. So,
also, I provide an automatic shifting device
105 to shift the vertical gear-carrying rod F at
the end of the route. This may consist of a
lever-arm, l' , depending from the car, its lower
end being in position to engage an incline, m' ,
on the trackway, its upper end being pivoted
110 to a horizontal thrust-bar, L' , which is formed
with an inclined slot, a' , engaging a stud-con-
nection of the vertical rod F at the lower end
of the latter. When the car reaches the end
115 of the route, the arm l' strikes the incline and
is shifted to move the thrust-bar and raise or
lower the vertical gear-rod, as the case may
be; and it is to be observed that the bevel-pin-
ions of the gear-rod F are located sufficiently
120 close to the journal-pinions of the rolls to pre-
vent entire disengagement at any time, for in
order to prevent the rolls from turning loosely
in shifting, the journal-pinions must be en-
gaged by the lower pinions of said rod before
the upper pinions are disengaged, and so, also,
125 of the reverse adjustment. In this manner
the movement of the rolls, and consequently of
the indicator-ribbon, is always under control.

A modification is illustrated in Figs. 16, 17,
and 18 of the drawings, in which the gearing
is somewhat simplified, the principle, how-
130 ever, remaining the same.

In addition to the names of the streets or

stations, advertising matter may appear upon the indicator-ribbon.

Having described this invention, what I claim, and desire to secure by Letters Patent, 5 is—

1. In a station-indicator, the combination, with the geared horizontal rolls and the indicator-ribbon, of the connecting and shifting rod F, having the intermediate gear, c, the 10 intermittently-moving barrel-gear engaging the gear c, and automatic devices governing its movements, substantially as specified.

2. In a station-indicator, the combination, with the upper geared roll and the lower spring-connected roll, its geared shaft, and the indicator-ribbon, of the vertical geared connecting rod F, engaging the gears e e' and the barrel-gear, the intermittently-moving barrel-gear engaging the gear c, and automatic 20 devices governing the movements thereof, substantially as specified.

3. In a station-indicator, the combination, with the geared horizontal rolls, the take-up spring, and the indicator-ribbon carried thereby, of the geared connecting-rod F, the barrel-gear in engagement therewith, and the winding-stem, an operating-spring in connection with said gear and winding-stem, the gearing and ratchet of the winding-stem, the stops 30 of the barrel-gear, the reciprocating toothed bar P, engaging the pinion M of the barrel-gear, and the adjusted stop-pawl, substantially as specified.

4. In a station-indicator, the combination, 35 with the horizontal geared rolls and the indicator-ribbon connected thereto, the geared connecting-rod, and stop-governed intermittent winding and let-off mechanism, of a vertically-reciprocating thrust-bar, T, in the casing J, provided with the inclined slot I for actuating the toothed rack-bar, the horizontally-reciprocating thrust-bar J', seated in the bearing Q, and having the beveled end to engage in arm d' of the rock-shaft e', and connecting 40 devices, substantially as specified.

5. In a station-indicator, the combination, with the ribbon-carrying rolls, the indicator-ribbon, and the gear-connections, of the winding mechanism, consisting of the bar P, operating upon the gear M, the stem K, and the 50 spring H in the barrel-gear, and the automatic stopping mechanism, consisting of the stop-pawl p, pivoted to the frame-plate, and having the projection v, to bear upon the stop-lugs n in the barrel G, substantially as specified. 55

6. In a station-indicator, the combination, with the ribbon-carrying rolls, the indicator-ribbon, and the gear-connections, of the main-spring and winding-gear, the reciprocating toothed bar engaging the gear M, thrust-bars 60 T and J', the trip-arm V, extending through the bearing v', and having the roller z at its lower end to engage a rack on the trackway, and the link-connection t, pivoted at its lower end to a crank on the roller-journal and its upper end to the crank-arm z', and the crank and other connections, substantially as specified. 65

7. In a station-indicator, the combination, with the ribbon-carrying rolls, the indicator-ribbon, and gear-connections, the mainspring, 70 and winding-gear, of a reciprocating thrust-bar having a beveled operating-surface and extended to provide a straight bearing surface, K', in the direction of motion, substantially as specified. 75

8. In a station-indicator, the combination, with the drum B, the free drum C, and the vertical geared rod F, of the shaft B, within the drum C and connected thereto by the spring D, designed to take up the ribbon slack, 80 substantially as specified.

In testimony whereof I affix my signature in presence of two witnesses.

MARK ANTHONY.
